UNITED STATES PATENT OFFICE.

EDWARD S. DAY, OF EAST BOSTON, MASSACHUSETTS.

FLY-CATCHER.

1,118,845.

Specification of Letters Patent. Patented Nov. 24, 1914.

Application filed May 1, 1913. Serial No. 764,780.

To all whom it may concern:

Be it known that I, EDWARD S. DAY, a citizen of the United States, residing at East Boston, in the county of Suffolk and 5 State of Massachusetts, have invented certain new and useful Improvements in Fly-Catchers; and I do hereby declare the following to be a full, clear, and exact description of the invention, such as will enable others skilled in the art to which it 10 appertains to make and use the same.

The present invention relates to fly catchers, and more particularly to fly catchers in which the flies are caught upon an adhesive 15 coated paper.

The object of the present invention is to provide a cheap and effective fly catcher in which a hollow collapsible paper body is expanded and securely held upon a saucer-like 20 holder.

With the above object in view, the present invention consists in the fly catcher herein-after described and particularly pointed out in the claim.

25 In the drawings, which illustrate the preferred embodiment of the invention, Figure 1 is a perspective view of the fly catcher; Fig. 2 is a vertical section through the lower part of the paper body and the holder; and 30 Fig. 3 is a plan view of the paper body collapsed for packing.

In the illustrated embodiment of the present invention, the flies are caught upon the surface of the paper body 1 which is coated 35 with an adhesive and which has, when expanded, the shape of a four-sided truncated pyramid. This paper body is formed of a single sheet of paper having its edges stuck together at 2 and folded into the pyramidal 40 shape. These adhesive coated paper pyramids, when they are packed for shipping, are folded flat, as shown in Fig. 3, so that a large number of them can be packed in a comparatively small box. In the four sides 45 of the paper pyramid near the bottom edge are holes 3, and in two opposite sides of the pyramid near the top edge are holes 4. The paper pyramid 1 is held expanded by means of a square sheet-metal saucer-like holder 5 50 which has an upturned rim 6 and an elevated central portion 7, which forms with the upturned rim 6, a trough 8 into which the bottom edge of the paper fits. The holders 5 are very cheap to manufacture since

they are stamped by means of dies from a 55 single piece of sheet metal, and the tongues 9 are cut from the metal sheet itself. Pointed tongues 9 are stamped out of the inside wall of the trough 8 and project laterally from the elevated central portion 7 through 60 the holes 3 in the bottom of the paper pyramid to hold the holder 5 and the pyramid 1 together. The holder 5 also forms a protecting stand so that the sticky fly catcher may be set down without damage to the 65 article upon which it is placed. A wire bail 10 is received through holes 4 for suspending the fly catcher.

To attach the tubular paper body to the base, it is simply necessary to unfold it 70 until its shape is approximately rectangular in cross section and then press the lower end of the tubular body down over the part 7 of the base. As the end of the tube slips down over the enlargement 7, the lower 75 edges of its side walls will sufficiently flex outwardly to slip down over the hooks 9 and cause said hooks to engage the openings 3 and thus lock the paper tube to the saucer-like base. When it is desired to remove the 80 tube and replace it with a new one, it is simply pulled off the base with sufficient force to cause the hooks to tear the walls of the paper tube between the holes or eyelets 3 and the lower edge of the tube. It 85 will be seen, therefore, that the ready means I provide for attaching and detaching the tubes as well as the cheapness of the tube 90 will enable me to supply a large number of tubes for use on a single base; and to further increase the commercial value of my device the paper tube may be of the collapsible variety, since the base saucer is adapted 95 to hold the tube against collapsing when it is attached thereto. It will be seen also that it is important that the wall or walls 100 of the tubular body shall be sufficiently stiff to be self-sustaining, so as to thereby be supported in an upright and expanded position within the saucer solely by the saucer.

The present invention is not limited to its illustrated embodiment, but may be embodied in other constructions within the scope of the invention as set forth in the following claim:—

A fly catcher having, in combination, a hollow tubular paper body coated exteriorly with an adhesive and having a plurality of

spaced holes near its lower edge, and a saucerlike holder having an upturned rim and an elevated central portion fitting within the open bottom of the paper body, and a plurality of tongues projecting outwardly and downwardly from the walls of said elevated central portion at points a distance

from its lower edge, these tongues extending through the holes in the paper body, for the purposes set forth.

EDWARD S. DAY.
